COIN HOLDER ATTACHMENT FOR AUTO-
MOBILE VISORS OR THE LIKE

Bernard Katz, Chicago, Ill., assignor to World
Wide Plastics Corporation, Chicago, Ill., a cor-
poration of Illinois

Application November 4, 1952, Serial No. 22,119

Term of patent 7 years

(Cl. D52—4)

To all whom it may concern:

Be it known that I, Bernard Katz, a citizen of the United States and resident of Chicago, in the county of Cook and State of Illinois, have invented a new, original, and ornamental Design for a Coin Holder Attachment for Automobile Visors or the like, of which the following is a specification, reference being had to the accompanying drawings, forming a part thereof.

Fig. 1 is a front elevational view of a coin holder attachment for automobile visors or the like showing my new design;

Fig. 2 is a rear elevational view of the same;

Fig. 3 is a side elevational view as viewed from the right side of the coin holder attachment for automobile visors or the like as illustrated in Fig. 1 of the drawings;

Fig. 4 is a view similar to that of Fig. 3 but as viewed from the opposite side;

Fig. 5 is a top plan view of the coin holder attachment for automobile visors or the like; and
Fig. 6 is a bottom plan view of the same.

I claim:

The ornamental design for a coin holder attachment for automobile visors or the like, substantially as shown.

BERNARD KATZ.
